[57] CLAIM

The ornamental design for an upside down fishing net, as shown and described.

DESCRIPTION

FIG. 1 is an environmental perspective view of a upside down fishing net showing my new design;
FIG. 2 is a front elevational view thereof;
FIG. 3 is a rear elevational view thereof;
FIG. 4 is a right side elevational view, the left side being a mirror image thereof;
FIG. 5 is a top view thereof;
FIG. 6 is a bottom view thereof; and,
FIG. 7 is a front elevational view with the device in the open position.
The broken line showing of the fish and fishing line in FIG. 1 is for illustrative purposes only and forms no part of the claimed design.
